CLOSURE STRUCTURE

Filed Dec. 17. 1931

UNITED STATES PATENT OFFICE

1,928,913

CLOSURE STRUCTURE

Lyle K. Snell, Detroit, Mich., assignor to Eaton Manufacturing Company, Cleveland, Ohio, a corporation of Ohio

Application December 17, 1931
Serial No. 581,673

2 Claims. (Cl. 220—24)

This invention relates to closure devices of the type used on the radiators and fuel tanks of motor vehicles, and as one of its objects aims to provide a closure device of this kind embodying a novel means for facilitating the mounting of a display thereon.

Another object of my invention is to provide a hinged bayonet-type closure embodying a pivot member adapted to receive the securing portion of a display device.

A further object of this invention is to provide a closure of the type referred to, wherein a hinge pivot member is provided with means for indicating the size and location of an opening for the securing means of a display device.

Other objects and advantages of this invention will be apparent from the following description when taken in conjunction with the accompanying sheet of drawing, wherein:

Fig. 1 is a sectional elevation of a closure device embodying my invention;

Fig. 2 is a bottom plan view thereof;

Fig. 3 is a partial sectional elevation of my closure device before the display has been mounted thereon;

Fig. 4 is a bottom plan view thereof; and

Fig. 5 is a partial sectional elevation showing another form of mounting means for the display.

In the drawing, to which detailed reference will now be made, I have shown a closure device of the type disclosed in my copending application Serial No. 549,956, filed July 10, 1931. As disclosed in said application, my closure device is of the bayonet type and comprises a member having an opening to be closed, such as the tubular filler neck 10, and a closure 11 connected thereto by means of the hinge linkage 12. The tubular member to be closed may be secured to the wall of a fuel tank, radiator, or other receptacle, and is provided at its outer end with a laterally extending flange 13 forming one part of a bayonet locking device and also providing a seat for the gasket 14.

The closure itself may be of any appropriate construction and, as shown in this instance, comprises a body having a shell composed of outer and inner sheet metal walls 15 and 16, which walls are secured together in any suitable manner, with a chamber therebetween. A locking spring 18, which is secured to the inner wall 16, as by means of the rivets 19, is provided with oppositely extending resilient cam fingers 20. These cam fingers are shaped and arranged to pass through the notches or openings 21 of the flange 13, and to cooperate with the under sur-

face of the latter upon relative rotation between the closure and the tubular member.

The hinge linkage, as shown in this instance, comprises a bracket 22 secured to the wall of the tubular member, and a link 23 pivoted at one of its ends to the bracket 22 and at its other end to a bracket 24. The latter bracket is, in turn, pivotally connected to the inner wall 16 by means of the pivot member 25. This hinge linkage permits the closure to be swung to an open position which is entirely clear of the filling opening, and when the closure is swung to the closed position, shown in Fig. 1, it recedes in the filling opening. The pivotal connection between the wall 16 and the bracket 24 allows the closure to be rotated relative to the tubular member for locking and unlocking purposes.

As thus far described, my closure device is of substantially the same construction as the device disclosed in my copending application referred to above. I have found, however, that it is frequently desirable to mount a display, such as the ornamental figure 26, upon the outer wall of the closure. This can be best done by drilling a hole through the pivot member 25, and through the outer wall 15, to receive the securing stem or portion 27 of the display. I have also found that, in drilling this hole through the pivot member 25, great care must be exercised to locate the hole exactly on the axis of the pivot member so that the opening being formed will not break through the wall of this member. It is also important that the opening to be formed in the pivot member be of the proper size so that when the securing portion 27 is mounted therein, the liquid of the container will not escape around this securing portion.

As shown in the drawing, the pivot member 25 is constructed with a shouldered stem portion 28, upon which the hinge member or bracket 24 is pivoted, and a head portion 29 for retaining the member 24 upon the stem portion. For conveniently securing the pivot member to the wall 16 of the closure, I construct this member in the form of a hollow rivet having a sleeve portion extending through the wall 16 and riveted over to form the head 30. For the purpose of indicating the exact location for an opening through the pivot member, should one be desired for the securing portion of a display, I provide the drill centering recess 31, as shown in Fig. 3 of the drawing. In addition to this drill centering recess, which is located exactly on the axis of the pivot member, I provide a shallow depression or counterbore 32 having a diameter exactly equal

to the diameter of the opening in the riveted sleeve portion of the pivot member. Thus it will be seen that, as initially constructed, my closure device is provided with a hinge pivot member 5 having a drill centering recess in the head thereof, and also having a counterbore indicating the maximum size of drill which may be used without breaking through or injuring the stem portion of the pivot member.

10 When the owner of the closure device desires to apply an ornament, or other display device, to the closure, it is only necessary for him to drill outwardly through the pivot member 25 and through the outer wall 15. During this operation, a drill is employed of not larger diameter than the diameter of the counterbore 32, which drill is centered for the drilling operation in the recess 31. Although the opening initially formed in the wall 15 is of the same diameter as the hole 20 drilled through the rivet, this opening may subsequently be enlarged to accommodate any size of securing portion. After openings of proper size have been drilled through the pivot member and the wall 15, the securing portion of the display device is inserted through these openings and may be retained against withdrawal by means of the nuts 33, or any other suitable securing means.

25 To prevent the top wall of the closure from being bent or distorted when the nuts 33 are tightened, I prefer to provide the securing stem or portion 27 of the display with a shoulder 34 which is properly located to engage the riveted head portion 30 of the pivot member 25. Instead of employing an integral shoulder for this purpose, as shown in Fig. 1, it may be desirable to provide the tubular spacer 35 shown in Fig. 5, in which case the securing stem 27' may be of uniform size throughout its length. When such 40 a spacer is employed, this member extends between the under side of the display 26' and the riveted head 30' of the pivot member 25'.

It will now be readily see that I have provided

an improved form of hinged closure device upon which an ornament or display may be readily mounted with a securing portion extending through the hinge pivot member of the closure. Moreover, it will be seen that by my invention I have provided simple and reliable means for accurately indicating the size and location of the opening to be drilled for the securing portion of the display, thereby eliminating the danger of the closure device being ruined by an improperly drilled hole.

80 While I have illustrated and described my invention in a detailed manner, it should be understood, however, that I do not intend to limit myself to the precise details of construction and arrangements of parts illustrated and described, but regard my invention as including such changes and modifications as do not involve a departure from the spirit of the invention and the scope of the appended claims.

90 Having thus described my invention, I claim:

1. The combination with a radiator cap having outer and inner walls with a chamber therebetween, of means for mounting a display on said cap comprising a member having a stem portion extending through the inner wall and having a head portion on each side of the latter, one of such head portions having a drill-center therein located on the axis of said stem portion for facilitating forming an opening through said member for use in securing said display on the cap.

105 2. The combination with a radiator cap having spaced outer and inner walls, of means for mounting a display on said cap comprising a member having a hollow stem portion extending through the inner wall and having head portions on opposite sides of said inner wall, the head portion of said member which is most remote from the outer wall having a recess therein for indicating the location and size of the opening in said 110 hollow stem portion.
